UNITED STATES PATENT OFFICE

MARTIN HENRY GATELY, OF HENDERSON, NEBRASKA

MACHINE FOR GRINDING FORAGE

Application filed December 3, 1927, Serial No. 237,530. Renewed February 25, 1932.

The object of this invention is to provide a machine in which the incoming material is moved by a conveyor beneath a series of longitudinally extending toothed devices, termed 5 fishbacks, the series including both stationary and swinging elements, said elements serving to cut the ties from the bundles, divide the stalks, and carry the material to a rotary grinding device cooperating with 10 stationary grinding elements, including a toothed concave, the material passing thru a screen of a degree of fineness suitable for the product, before being discharged in position for reception by an elevator and 15 loader.

A further object is to employ a construction of the type indicated in which the current of air created by the movement of the rotary grinding element will facilitate the 20 grinding operation, and further to employ a machine of economical and durable construction which will be under the control of a governor of the type disclosed in my co-pending application, Ser. No. 237,531, in 25 which a special form of clutch is claimed,— said governor insuring a pickup at a uniform low speed regardless of the load, and acting to stop the machine if the latter is materially retarded in operation from any 30 cause. The application named has matured into Patent No. 1,720,952.

A further object is to employ improved grinding elements, mounted in an improved manner.

With the foregoing and other objects in view, the invention consists in the novel construction and arrangement of elements described, illustrated and claimed, it being understood that modifications may be made 40 within the scope of the claim without departing from the spirit of the invention.

In the drawings forming part of this application,

Figure 1 is a view showing the operative elements, chiefly in elevation, a portion of the housing being removed.

Figure 2 is a plan view of the structure of Figure 1 with a portion of the housing broken away.

Figure 3 is a horizontal section, on line 3—3 of Figure 1.

Figures 4 and 5 are perspective views of devices in the upper central part of Figure 1 between which the material passes in flowing from the conveyor into the grinding element or elements.

Figure 6 is a section on line 6—6 of Figure 3, showing one of the grinding devices, and the manner of mounting the latter.

Figure 7 is a section on line 7—7 of Figure 1.

Figure 8 is a section on line 8—8 of Figure 1.

Figures 9 and 10 are views in section thru the fishbacks, or stationary and movable feeding elements at the upper central portion of Figure 1, and Figure 9 being on line 9—9 of said Figure 1.

The material to be ground is carried by conveyor 10 mounted in frame 11, beneath the fishbacks in the upper central portion of Figure 1, and passes thru opening 12 to the housing 13 of the grinder per se. A plate 14 is mounted at 15 for swinging movement just within opening 12, and serves as a shield and in turn to direct the material over the pan or apron 16, illustrated in detail in Figure 4. This device being pivoted at 17, and including an end portion which extends just below the discharge end of the conveyor 10. This conveyor may be of any suitable type, including sprocket chains and transverse bars or slats designated 10'. The chains pass over wheels on shafts 20 and 21, an 45 idler being shown at 22. A supporting device or leg member 23 is mounted below the middle portion of the conveyor frame, being pivoted at its lower ends, as shown at 24 and connected by means of a chain or the like 50 25 with the middle portion of the housing of the grinder.

The conveyor frame 11 mounts upper extensions or side members 27, and between side members 28, I mount a plurality of fishbacks 55 or feeding devices. These elements may be of inverted channel shape, and are shown in cross section in Figures 9 and 10, the flanges of the channels each carrying a series of teeth as indicated in Figure 1, these teeth be-

ing cut in a direction to permit of the feeding of the material from the conveyor to the housing of the grinder, or to aid in such feeding and to impart a preliminary separation or abrasive action.

- 5 The fishbacks thus formed and designated 30, 31 and 32 are movable, being mounted for swinging action, in view of the chain connection 33, and the link connection 34, the element last named constituting an arm mounted radially with reference to shaft 35 to which movement is imparted from shaft 36, by eccentric or crank elements, as indicated at 37.
- 10 The movable fishbacks 30, 31, 32 are connected by cross bars 38, and the stationary fishbacks 40 and 41 are connected by transverse bars 42. These bars last named are mounted at their ends as shown at 43.
- 15 The shaft 36 carries a fly wheel 44, normally loose on the shaft but adapted for operative connection with the shaft when a predetermined minimum speed has been imparted to the fly wheel, as disclosed in my 20 aforesaid pending application.

25 The shaft 36 carries a pulley wheel 46, and belt 47 passes over this wheel and over pulley wheel 48 on shaft 49 of the rotary grinder shown in Figures 1 and 3. This grinder includes the spider elements 50 and 51, each having a hub portion, such as 52 providing bearings for mounting the grinder on shaft 49. Transverse bars 54 extend between the spider elements 50 and 51 and mount the 30 grinders or cones 55, of the form shown in the detail views, these devices being secured by bolts or stems 56 and nuts 57. These devices 55 have a corrugated or spirally channeled surface, providing a most effective form 35 of abrasive element.

40 Stationary grinding elements, also of cone form, and designated 60, cooperate with the elements 55, and are of course mounted to provide the proper spacing between said stationary elements and the elements mounted on the rotatable device or principal grinder. A concave 62 extends between the mounting element 61 of the stationary grinders, and the discharge opening, in the lower central 45 portion of the housing, and designated 63. This concave is provided with a corrugated or other suitable form of grinding surface for effecting further abrasive action before the discharge of the material thru opening 50 63, and the teeth or corrugations on element 62 tend to hold the material until fully ground.

55 A screen 65 is mounted between the guiding devices 66 in the housing and is detachable, 50 permitting of the use of a screen having perforations or apertures therein of a size suitable for the grinding operation under way, in order to effect the exact separation or screening desired. A plurality of screens, with 55 openings of different size, and different

forms, will be provided for use with the machine.

The mounting of the grinding devices is illustrated in detail, especially in Figures 6, 7 and 8, and the mounting of the fishbacks is 70 shown in cross section in Figures 8, 9 and 10, the movable or oscillating elements being designated 30, 31 and 32, and the stationary fishbacks being designated 40 and 41.

The material is fed into the machine easily 75 and in a steady and uniform manner, by the fishbacks cooperating with the feeding conveyor. On the return stroke of the movable fishback elements, the material is held by the stationary fishbacks which further prevent the material from being acted upon by the suction of the rotating grinder prior to entry of said material into the housing of this grinder.

80 The governor referred to as being disclosed in another application is an important element in the production of uniform feed and in control or automatic release under the conditions stated.

85 The material to be ground by the rotatable grinding element first passes the swinging gate 14, and is deflected from the upper inner wall of the housing 13, and thence downwardly onto the rotary element, and the pan or chute 16 below the member 14 90 materially facilitates distribution, causing the material to move in the right direction, while baffle plate 16' keeps it from passing in front of the screen before being ground. The principal grinding operation is effected 100 between the cone shaped corrugated moving grinding elements and the stationary members similarly formed, and the corrugated plates and the teeth of the rotary element, all material being discharged thru the 105 lower opening of the housing, but any portion not discharged is carried around a second time for further passage thru the machine, following the course indicated for that portion of the material, the movement of 110 which is described in detail.

What is claimed is:

115 In a machine for grinding forage, a grinding element, a housing within which the element is mounted, a travelling feeding device, alternate oscillating and stationary feeding devices, of channel type, positioned above the travelling element and means for moving the oscillating devices in a curved path 120 for engaging material on the travelling element, these means including crank hangers movable about a common axis near corresponding ends of the channel devices; and devices comprising relatively movable members supporting the opposite end portions of 125 the movable channel elements, permitting variable oscillating movement thereof.

130 In testimony whereof I affix my signature.

MARTIN HENRY GATELY.
